UNITED STATES PATENT OFFICE

BYRON M. SCHMUHL, OF CENTERLINE, MICHIGAN, ASSIGNOR OF ONE-THIRD TO WM.
CADZOW RAMSAY, OF DETROIT, MICHIGAN

BATTERY POST CLAMP

Application filed April 27, 1929. Serial No. 358,487.

My invention relates to a new and useful improvement in a battery post clamp and has for its object the provision of a battery post clamp which will prevent corrosion.

5 Another object of the invention is the provision of a clamping member in a battery post clamp whereby the battery post clamp may be easily and quickly moved from clamping to unclamped position.

10 Another object of the invention is the provision of a battery post clamp having a swingable member for supporting an absorbent pad in contact with the battery post.

Another object of the investigation is the 15 provision of a battery post clamp which will be simple in structure, economical of manufacture and highly efficient in use.

Other objects will appear hereinafter.

The invention consists in the combination 20 and arrangement of parts hereinafter described and claimed.

The invention will be best understood by a reference to the accompanying drawing which forms a part of this specification, and 25 in which,

Fig. 1 is a top plan view of the invention showing the absorbent pad in inoperative position.

Fig. 2 is a top plan view of the invention 30 showing the device in operative position.

Fig. 3 is a side elevational view of the invention showing it applied.

Fig. 4 is a sectional view taken on line 4-4 35 of Fig. 3.

Fig. 5 is a sectional view taken on line 5-5 40 of Fig. 2.

In the drawing I have illustrated the invention applied to battery post 10 which projects upwardly from a battery 9. A substantially U shaped clamping member 11 is adapted to embrace the battery post 10, this clamping member having the outwardly turned ends 12 and 13. A sleeve 14 is carried by the battery clamping member 11 to which is attached the cable 15. Projected through the outwardly turned ends 12 and 13 is a bolt 16 on which is threaded the nut 17.

A plate 19 is provided on its undersurface with an absorbent pad 20 which may be saturated with oil, paraffin, or the like. A tongue

22 pressed from the plate 19 serves to bind the pad 20 thereon and to form the hole 21 through which lubricant may be poured onto the pad 20. Spaced lugs 23 and 24 project downwardly from one end of the plate 19 and are pivoted to the head 18 of the bolt 16. As shown in Fig. 3 these lugs are at an inclination to the plane of the plate 19 so that operating on the outwardly turned end 13 they have a cam effect and when the plate 19 is moved to the position shown in Fig. 3 they serve to clamp the member 11 about the post 10 and to lock the plate 19 so that the pad 20 engages the upper end of the post 10 and the clamping member 11.

Another object of the invention is the provision of a finger grip 25 projects from one side of the plate 19.

With a device of this class, corrosion is prevented and a clamp afforded whereby the device may be easily and quickly attached to a battery post.

While I have illustrated and described the preferred form of my invention I do not wish to limit myself to the precise details of structure shown, but desire to avail myself of such variations and modifications as may come within the scope of the appended claims.

Having thus described my invention, what I claim as new and desire to secure by Letters Patent is:

1. A battery post clamp of the class described comprising: a clamping member for clamping about a battery post and having its ends angularly turned and in spaced relation; a bolt projected through said angularly turned ends; a nut threaded on said bolt; a head on said bolt; a cover swingably mounted on said head; a laterally projecting portion on said cover for overlying the battery post; and cam extensions on said cover for moving said ends into approach upon movement of said cover to operative position.

2. A battery post clamp of the class described, comprising: a substantially U-shaped clamping member for clamping about a battery post and having its legs projected outwardly beyond one side of said post in substantially parallel relation to each other; a bolt projected through said outwardly projecting portions of said legs; a nut threaded

on said bolt; a head on said bolt; a cover swingably mounted on said head and a laterally extended portion on said cover adapted, upon movement of said cover to closed position, for overlying the battery post.

In testimony whereof I have signed the foregoing specification.

BYRON M. SCHMUHL.
